MANUAL SHARPENING IMPLEMENT

Blackwell K. Murchison, Brooklyn, N. Y., assignor, by mesne assignments, to Bessie F. Murchison, Brooklyn, N. Y.

Application September 29, 1950, Serial No. 187,387

7 Claims. (Cl. 51—214)

1

This invention relates to new and useful improvements in manual sharpening implements.

The dominating object of this invention resides in the construction of a manual sharpening implement which has one set of spaced sharpeners and a cooperative set of meshing guides, or meshing sharpeners, associated with means by which the sharpeners, or guides, may be moved to various relative positions so that portions of the sharpeners are exposed to use during the use of the implement. With this construction it is possible to change the meshing relation of the sharpeners, or sharpeners and guides, so that fresh portions of the sharpeners are exposed to use when desired. The invention contemplates a simple and novel adjustment by which the sharpeners, or sharpeners and guides, may be adjusted as stated.

Another and important feature of this invention resides in replaceably mounting the sharpeners in position so that worn sharpeners may be removed and replaced as required.

Another and important feature of this invention resides in providing the sharpeners with working faces which are arranged at selected angular positions. In accordance with this invention the angles may vary from a few degrees upwards to 90° or more, if so desired. With this construction the sharpening implement may be designed to sharpen knives, cleavers, scissors, razors, and many other articles.

Another object of this invention resides in providing the sharpening implement with one set of spaced sharpeners and meshing guides in those implements intended to sharpen one face of an object at a time, and to provide two sets of spaced meshing sharpeners in those implements intended to sharpen two faces at a time.

It is also proposed that the sharpeners be constructed of various types and kinds of sharpening materials containing various types and kinds of grits of various fineness or coarseness. This large selection of grits makes it possible to use the sharpening implement to grind, hone or in other ways condition the edges of articles to be sharpened or treated. More particularly, it is contemplated that each sharpening implement be provided with different sharpening sections, one containing sharpeners suitable for grinding, and the other containing sharpeners suitable for honing, or in other ways finishing or conditioning edges.

Still another object of this invention resides in embodying the mesh move principal of spaced and meshing sharpeners, or sharpeners and

2

guides, into sharpening implements of various designs, as for example, implements having fingers grips, or having hand grips, or having more than one finger or hand grip.

5 Another object of the invention is the construction of a device as described which is simple and durable and which may be manufactured and sold at a reasonable cost.

For further comprehension of the invention, 10 and of the objects and advantages thereof, reference will be had to the following description and accompanying drawings, and to the appended claims in which the various novel features of the invention are more particularly set forth.

15 In the accompanying drawings forming a material part of this disclosure:

Fig. 1 is a plan view of a manual sharpening implement constructed in accordance with one form of this invention.

20 Fig. 2 is a sectional view taken on the line 2—2 of Fig. 1.

Fig. 3 is an end view of Fig. 2 looking from the left hand end.

Fig. 4 is an end view of Fig. 2 looking from 25 the right hand end.

Fig. 5 is a front elevational view of Fig. 2.

Fig. 6 is a front elevational view of another manual sharpening implement constructed in accordance with another form of this invention.

30 Fig. 7 is a fragmentary plan view looking in the direction of the line 7—7 of Fig. 6.

Fig. 8 is a front elevational view of still another manual sharpening implement embodying another form of this invention, one half of this view being shown partly in section to disclose the interior construction.

Fig. 9 is an end view of Fig. 8 looking from either end.

Fig. 10 is a fragmentary vertical sectional view taken on the line 10—10 of Fig. 8.

40 The manual sharpening implement, as illustrated in Figs. 1—5 inclusive, includes a pair of members 10 and 11 slidably connected with each other to move in a longitudinal line towards and away from each other. These members are slidably connected with each other by a stud 12 which is fixedly attached to the member 10 by a pin 13 and which engages through a tubular bearing 14 fixedly mounted on the member 11.

45 A plurality of spaced sharpeners 15 are mounted on one of these members, for example, the member 11. These sharpeners 15 are arranged in spaced positions spaced transversely of the line of sliding of the members 10 and 11. A plurality 50 of guides 16, or other sharpeners 16, are mount-

ed on the other of said members, namely, the member 10 and engage in the spaces between the sharpeners 15 for guiding an object to be sharpened across sections of the sharpeners 15. It is pointed out that if the parts 16 are guides then the sharpening implement sharpens one face of an object at a time, while if the parts 16 are sharpeners, then the implement sharpens two faces of an object simultaneously. The dot and dash lines 17, in Fig. 2, schematically indicates a knife engaging between the parts 15 and 16 in sharpening position. When this knife 17 is moved back and forth across the parts 15 and 16 its edge will be sharpened or honed, or conditioned, depending upon the nature of the parts 15 and 16, specifically, whether these parts are grinding elements, honing element, other conditioning elements, or guiding elements.

The members 10 and 11 are associated with means by which said members may be moved into selective positions towards and away from each other along the longitudinal line of sliding of the members 10 and 11 for controlling the sections of the sharpeners 15, or 15 and 16, engaged by an object such as the knife 17 when the implement is being used. Said means for moving said members 10 and 11 includes an expansion spring 19 coaxially mounted on the stud 12, and having its ends engaging in recesses 20 and 21 formed in the adjacent faces of the members 10 and 11. A nut 22 threadedly engages on the end of the stud 12 and indirectly controls the compression of the spring 19. A handle 23 by which the implement may be conveniently handled is connected with the member 11. Studs 24 for connecting the handle 23 with the member 11 are fixedly mounted either on the member 11 or on the handle 23 and slidably engage in aligned openings either on the handle 23 or the member 11, depending upon which of these parts the studs are fixedly mounted. The handle 23 has a cutout 25 into which the nut 22 is set. The nut 22 acts against a portion of the handle 23 and in this way moves the member 11 towards the member 10, when the nut is turned in one direction, or permits the spring 19 to move the member 11 away from the member 10 when the nut 22 is turned in the other direction.

The members 10 and 11 are of identical shape, each having a wide section 25 and a narrow section 26. These sections extend from the centers of the members outwards. However, the members 10 and 11 are turned so that the wide section 25 of the member 10 is at the top and is opposed to the narrow section 26 of the member 11. The wide section 25 of member 11 is provided with a pair of projecting studs 27 which engage against the sides of the narrow section 26 of the member 10 to hold the members 10 and 11 from pivoting on the stud 12 as an axis. In the particular sharpening implement illustrated the wide sections 25 are provided with two of the sharpeners 15 or 16, while the narrow sections 26 are provided with one of the sharpeners 15 or 16. These parts 15 and 16 mesh with each other as may be noted by examining Figs. 1, 2 and 5.

The parts 15 and 16 are removably mounted on the members 11 and 10. More specifically, the members 11 and 10 are formed with grooves 28 into which the parts 15 and 16 are set. Small screws 29 threadedly engage the members 10 and 11 and extend into the grooves 28 and against one of the edges of the parts 15 and 16 for clamping these parts against the other sides of the grooves 28. The screws 29 thus serve to releas-

ably hold the parts 15 and 16 in position. When these parts become worn they may be removed and replaced. The handle 23 is provided at the top with the word "Grind," indicated by reference numeral 30, and at the bottom with the word "Hone," indicated by numeral 31. These legends indicate the nature of the sharpeners 15 and 16. The sharpeners adjacent the legend "Grind" contain coarse grit so that they grind an object engaged against these sharpeners, while the sharpeners adjacent the legend "Hone" contain fine grit so that they hone or condition an object engaged against them.

The operation of the device may be understood from the following:

The implement is held by the handle 23. This handle 23 is relatively small so as to be capable of being held by the fingers. A knife or other object to be sharpened is merely moved back and forth between the adjacent faces of the sharpeners 15 and 16, or the adjacent faces of the sharpeners 15 and the guides 16 in the event that the parts 16 are guides and not sharpening elements. The parts 15 and 16 have adjacent faces 25 which are at fixed angular positions relative to each other. These angular positions control the angle of the bevel of the knife or other object which is to be sharpened. It is proposed that the sharpening implements be provided with parts 15 and 16 of selected angular positions. Thus one may purchase an implement with the sharpeners 15 and 16 at an angular position for sharpening knives. Or an implement may be purchased with the angular position for sharpening cleavers. Sharpeners may also be provided with an implement, to be replaced for the parts 15 and 16 for providing different angles of sharpening. These angles may vary from a few degrees for razors to very wide angles for cleavers and other objects.

It should be noted by examining Fig. 2 that the knife 17 engages the sharpeners 15 and 16 at the junction between their crossing faces. When this junction becomes rutted after some use it is merely necessary that the adjustment nut 22 be turned in one direction or the other so as to move the sharpeners 15 and 16 together or apart so as to change the junction between these sharpeners so that new sections of the sharpeners are now available for use. The adjustment nut 22 may be controlled so that the entire working surfaces of the sharpeners 15 and 16 are utilized at one time or another during the use of the implement. When the sharpeners 15 and 16 become thoroughly worn they are replaced.

In Figs. 6 and 7 a modified form of the invention has been disclosed which distinguishes from the prior form in several ways, particularly, this implement is provided with a hand grip 35 by which it may be gripped and handled. One end of this hand grip is provided with the members 10 and 11. These 10 and 11 members are associated with the other parts as shown in Figs. 1-5 inclusive. The operation of this sharpening implement is identical to the prior form.

The other end of the handle 35 is provided with an implement of a somewhat different construction. This construction includes a pair of members 36 and 37 slidably connected with each other to move in a longitudinal line towards and away from each other. One end of the handle 35 is connected with the member 36. This is accomplished by studs 38 mounted either upon the handle 35 or on the member 36 for engaging openings in the other adjacent part. The members

36 and 37 are slidably connected with each other by studs 39 which are mounted on one of these members and engage in complementary openings in the other of these members to control the longitudinal sliding thereof. A stud 40 is fixedly mounted on the member 37 by a pin 41 and engages through the member 36 and through a bearing 42 fixedly mounted on the member 36. This stud 40 also extends through the handle 35. Stud 40 is provided with an adjustment nut 43 which threadedly engages on the end portion of the stud 40. An expansion spring 44 is coaxially mounted on said stud 40 and acts between the adjacent faces of the members 36 and 37 for urging them apart. A plurality of spaced 15 sharpeners 45 are mounted on one of said members, namely, the member 37. These sharpeners are spaced transversely of the line of sliding of the members 36 and 37. Guides 46 are mounted or fixed upon the other of said members, namely, the member 36 and engage in the spaces between the sharpeners 45 for guiding an object to be sharpened across sections of the sharpeners 45. The sharpeners 45 are mounted in grooves 47 formed in the member 37. Screws 48 threadedly 20 engage the member 37 and engage one of the ends of the sharpeners 45 for releasably holding the sharpeners in position. The sharpeners may therefore be removed and replaced when they become worn.

The sharpeners 45 have working faces at a selected angle. For example, this angle may be such as to coincide with the angle on the blades of a pair of scissors. The dot and dash lines 50, in Fig. 6, indicate one of the blades of a pair of scissors engaged against the top sharpeners 45. The beveled edge of the blade 50 engages the sharpeners 45, while the straight side of the blade engages the end of the guide 46. The scissor blade 50 may be drawn back and forth over the sharpeners 45 for sharpening or conditioning the edge of the scissor blade. The handle 35 is imprinted with legends "Grind" and "Hone" at the corners to indicate whether the adjacent sharpeners are for grinding or honing.

The operation and use of the above sharpening implement may be understood from the following:

Knives, cleavers and other similar articles may be ground, honed and conditioned upon the sharpening implement on the left end of the handle 35. Scissors and other similar objects may be ground, honed, and conditioned on the sharpening implement on the right hand end of the handle 35. The adjustment nuts 22 and 43 may be turned in one direction or the other to vary the sections of the sharpeners engaged by the objects during the sharpening or conditioning operation. In other respects the operation of this form of the invention is identical to the prior form.

In Figs. 8-10 inclusive another form of the invention has been disclosed which distinguishes from the prior forms merely in construction. The operation and use of this implement is substantially the same as in the other forms. This implement includes a pair of members 50 and 51 slidably connected with each other to move in a longitudinal line towards and away from each other. A rod 52 is engaged through these members. This rod has a central square section 53 which engages square openings 54 in the members 50 and 51 by which the members 50 and 51 are slidably connected in a non-rotative manner. A handle 55 is connected with each of the mem-

bers 50 and 51. These handles 55 are in the form of tubes through which the ends of the rod 52 pass. A plurality of spaced sharpeners 56 are mounted on the members 50 and 51. These sharpeners are spaced transversely of the line of sliding of the members 50 and 51. The sharpeners 56 on one or the other of the members 50 and 51 may be replaced with parts of identical shape but comprising guides.

The members 50 and 51 are associated with means by which they may be moved towards and away from each other along their longitudinal line of sliding for controlling the degree of meshing of the sharpeners 56 of the members 50 and 51. This means includes an expansion spring 57 mounted on the square section 53 of the rod 52 between the adjacent faces of the members 50 and 51. The ends of the rod 52 are formed with threads 58. Nuts 59 are rotatively mounted on the ends of the tubular handles 55 and threadedly engage the threads 58. One or both of the nuts 59 may be turned for forcing the members 50 and 51 towards each other, or for permitting the expansion spring 57 to separate the members 50 and 51.

The sharpeners 56 are mounted in grooves 60 formed in the adjacent faces of the members 50 and 51. Small screws 61 are mounted on the members 50 and 51 and engage the ends of the sharpeners 56 for releasably holding them in position. The members 50 and 51 are imprinted with the words "Grind" and "Hone" (see Fig. 9) to indicate the nature of the adjacent sharpeners 56.

The operation of this implement may be understood from the following:

A knife or cleaver or other object to be sharpened is moved back and forth between the angular faces of the sharpeners 56 as seen in Fig. 8. 40 When the working portions of these faces become worn the nuts 59 may be turned so as to move the members 50 and 51 either together or apart, and in this way change the junctions of the working faces of the sharpeners 56.

45 While I have illustrated and described the preferred embodiments of my invention, it is to be understood that I do not limit myself to the precise construction herein disclosed and the right is reserved to all changes and modifications coming within the scope of the invention as defined in the appended claims.

Having thus described my invention, what I claim as new and desire to secure by United States Letters Patent is:

55 1. A sharpening implement, comprising a pair of spaced members having on their adjacent faces a plurality of meshing sharpeners and guides positioned above and below the centers of said members, a stud mounted at right angles through said members and at one end connected with one of said members, a nut threadedly engaging on said stud and selectively controlling the distance that said spaced members may move part for providing relative unyielding positions of mesh of said sharpeners and guides, and resilient means urging said members apart into said unyielding positions of mesh.

60 2. A sharpening implement, comprising a pair of spaced members having on their adjacent faces a plurality of meshing sharpeners and guides positioned above and below the centers of said members and said meshing sharpeners and guides having adjacent working surfaces diverging in the direction which extends from the centers of said members radially outwards, a stud attached

at one end to the center of one of said members and extending at right angles to said members and slidably passing through the center of the other of said members so that said members may move in a longitudinal line towards and away from each other, and a nut threadedly engaging on said stud and selectively controlling the distance that said spaced members may move apart for providing relative unyielding positions of mesh of said sharpeners and guides.

3. A sharpening implement, comprising a pair of spaced members having on their adjacent faces a plurality of meshing sharpeners and guides positioned above and below the centers of said members and said meshing sharpeners and guides having adjacent working surfaces diverging in the direction which extends from the centers of said members radially outwards, a stud attached at one end to the center of one of said members and extending at right angles to said members and slidably passing through the center of the other of said members so that said members may move in a longitudinal line towards and away from each other, a handle having a central opening by which it is engaged on said stud, and a nut threadedly engaging on said stud and abutting said handle and selectively controlling the distance that said spaced members may move apart for providing relative unyielding positions of mesh of said sharpeners and guides.

4. A sharpening implement as defined in claim

3, in which pins engage said handle and the adjacent one of said members for holding said handle from turning about said stud.

5. A sharpening implement as defined in claim 2, in which pins engage said members for holding them from turning relative to each other.

6. A sharpening implement as defined in claim 3, in which a tubular bearing is mounted on one of said members and engages in an opening in 10 said handle, and said stud passes through said tubular bearing.

7. A sharpening implement as defined in claim 1, in which said stud has a square section upon which said members are slidably mounted.

BLACKWELL K. MURCHISON.
